FOOD TRAY

Evan S. Connell, Jr., Kansas City, Mo.

Application February 13, 1951, Serial No. 14,209

Term of patent 14 years

(Cl. D44—10)

To all whom it may concern:

Be it known that I, Evan S. Connell, Jr., a citizen of the United States, residing at 2215 Drury Lane, Kansas City, and State of Missouri, have invented a new, original, and ornamental Design for a Food Tray, of which the following is a specification, reference being had to the accompanying drawing, forming part thereof.

I claim:

The ornamental design for a food tray, substantially as shown.

EVAN S. CONNELL, JR.
